SELECTIVE LENS SHADE AND FILTER CASE

Sol Tiffenberg, North Baldwin, and Leo Tiffenberg and Nathan Tiffenberg, Rosedale, N. Y.

Application April 2, 1953, Serial No. 24,312

Term of patent 14 years

(Cl. D61—1)

To all whom it may concern:

Be it known that we, Sol Tiffenberg, Leo Tiffenberg, and Nathan Tiffenberg, each citizens of the United States, and residents of 814 School Drive, North Baldwin, Long Island, New York, 234-20 129th Avenue, Rosedale, Long Island, New York, and 234-19 130th Avenue, Rosedale, Long Island, New York, respectively, have invented a new, original, and ornamental Design for a Selective Lens Shade and Filter Case, of which the following is a specification, reference being had to the accompanying drawing, forming part thereof.

Fig. 1 is a front perspective view of a selective lens shade and filter case in open position, showing our new design;

Fig. 2 is a front perspective view thereof showing the case in closed position;

Fig. 3 is a top plan view thereof, showing the case in open position and the upper layer thereof;

Fig. 4 is a top plan view thereof, showing the case in

Fig. 5 is a bottom plan view thereof, showing the case in open position, and the upper layer thereof; and

Fig. 6 is a cross-sectional view thereof taken on the line 6-6 of Fig. 2.

We claim:

The ornamental design for a selective lens shade and filter case, substantially as shown.
